US00D996213S

(12) **United States Design Patent** (10) Patent No.: **US D996,213 S**
(45) Date of Patent: **** Aug. 22, 2023**

(54) **LID FOR PACKAGING**

- (71) Applicant: **TETRA LAVAL HOLDINGS & FINANCE S.A.**, Pully (CH)
- (72) Inventors: **Paolo Zanon**, Modena (IT); **Anna Rosa Vietri**, Modena (IT); **Pietro Martini**, Parma (IT); **Marco Insero**, Bologna (IT)
- (73) Assignee: **TETRA LAVAL HOLDINGS & FINANCE S.A.**, Pully (CH)
- (**) Term: **15 Years**

(21) Appl. No.: **29/860,894**

(22) Filed: **Nov. 23, 2022**

Related U.S. Application Data

- (62) Division of application No. 35/512,506, filed on Mar. 5, 2021 (U.S. filing date under 35 U.S.C. 384), and having an international filing date of Mar. 5, 2021.

(30) **Foreign Application Priority Data**

CLAIM

The ornamental design for a lid for packaging, as shown and described.

DESCRIPTION

FIG. 1 is a right-side perspective view of a lid for packaging, showing our new design;

FIG. 2 is a right side view thereof;

FIG. 3 is a left side view thereof;

FIG. 4 is a rear view thereof;

FIG. 5 is a front view thereof;

FIG. 6 is a top plan view thereof; and,

FIG. 7 is a bottom plan view thereof.

The broken lines are shown for the purpose of illustrating parts of the article that form no part of the claimed design.

1 Claim, 7 Drawing Sheets
